UNITED STATES PATENT OFFICE.

ARTHUR H. SHOWALTER, OF BROOKLINE, MASSACHUSETTS, ASSIGNOR TO THE RUSSELL COMPANY, OF BOSTON, MASSACHUSETTS, A CORPORATION OF MASSACHUSETTS.

BOX CELL CASE.

Application filed April 17, 1920. Serial No. 374,570.

To all whom it may concern:

Be it known that I, ARTHUR H. SHOWALTER, a citizen of the United States, and a resident of Brookline, county of Norfolk, 5 State of Massachusetts, have invented an Improvement in Box Cell Cases, of which the following description, in connection with the accompanying drawings, is a specification, like characters on the drawings representing like parts.

This invention pertains to improvements in box cell cases, and more particularly, though not exclusively, to improvements in cell cases for boxes to contain bottles and 15 the like.

It is among the purposes of the invention to provide a box cell of moderate cost and of superior construction.

In the drawings, which show a preferred 20 form of one embodiment of my invention:—

Fig. 1 is a plan view of a box having a cell case and bottles therein;

Fig. 2 is a section on the line 2—2 of Fig. 1, being partly in elevation; and

Fig. 3 shows a preferred form of blank forming a partition of the cell case.

Referring to the drawings and to the preferred form of my invention selected for 30 illustrative purposes, I have shown a box 4 containing bottles 5 and a cell case, herein shown as formed of interlocked partitions 6 dividing the box into cells.

The partitions 6 are preferably slit at 35 their intersections in such manner as to provide not an absolute interlock, but what may be termed a frictional interengagement sufficiently strong to prevent accidental separation of the parts but adapted to permit very facile assembly of the parts, and even 40 disassembly thereof, even though the material of which the partitions are formed is relatively heavy, such for instance as a heavy fibreboard or cardboard.

The slits of adjacent crossing partitions 45 are preferably similar so that the same type of dies may be used to form the slots in all the partitions. The preferred form of slot shown in the drawings is of the interrupted type, the slot being initially interrupted at 50 8 by being narrowed, preferably by projections from each side of the slot, such projections preferably inclined toward the outer and inner portions of the slot. The slot is also, as illustrated, preferably inter-

rupted by a cross piece 9, preferably relatively short and segregating a portion of the slot as a hole 10, which may be of any suitable shape or size adapted to receive the projecting means 8 of the cooperating slot in the engaging partition. 55

Where the slots in cooperating blanks are to be similar, the partitions of the cell case are to be of substantially equal height, as illustrated, and the hole or depression 10 is preferably, as shown, located substantially the same distance from the adjacent margin of the blank as the projection 8 is located from the opposite margin of the blank. 60

When the blanks are assembled, the parts 70 will interengage very readily, the projections 8 of each set of blanks having only to crowd past the preferably relatively short interruption of cross pieces 9 of the other set of blanks, the partitions when assembled being 75 held in assembled relationship by the interengagement, at each intersection, of two sets of projections 8 entering two holes or depressions 9. The tapering of the projections 8 is superior to the more usual interlocking 80 hooks not only in that the parts may be more readily disassembled if desired, but also in that the projections 8 are greatly strengthened. As to disassembly, the parts 85 may be taken apart by application of substantially the same force required to assemble them, assuming the angular relations of intersecting partitions are the same.

The construction illustrated may be readily assembled with intersecting partitions at 90 right angles to each other. Sufficient interengagement is preferably provided so that the cell cases will not come apart even when collapsed by bringing the intersecting parts into approximate parallelism. 95

Where the cell case is to be used for bottles, it is highly desirable that means be provided for retaining the cell case in such position as to preclude the touching of adjacent bottom edges of adjacent bottles, these being 100 portions of bottles ordinarily relatively highly frangible.

I have found that the cell case may be held down in position by the bottles themselves, and to this end I preferably provide a portion of the cell case adapted to pass beneath one or more of the bottles. In the 105 form of my invention illustrated, one of the

central longitudinal partitions is provided with a bent-over extension 11 extending beneath the central longitudinal row of bottles. This bent-over extension may be formed integral with its cooperating partition, and, if desired, scored to facilitate the bending.

Even if a covered box containing the bottles be inverted, the cell case will remain in position, the flanged-over portion 11 holding the entire cell case adjacent the normal bottom of the box.

When the box is empty the cell case may be readily removed and collapsed without interference by the flange 11, the latter being, if desired, bent back into the plane of the box partition to which it is primarily attached.

While I have shown and described a preferred form of my invention, it will be understood that major changes may be made including omission, substitution, alteration and reversal of parts, without departing from the scope of my invention, which is best defined in the appended claims.

Claims.

1. A cell case comprising intersecting partitions and frictionally interengaging semi-locking means at points of intersection of said partition, said semi-locking means permitting disassembly of said cell case by a unidirectional separating force while the intersecting partitions are substantially at right angles to each other.
2. A blank for a cell case slotted through a portion of its height and provided on at least one side of the slot with a projection into the slot, said projection having relatively gradually sloping surfaces at both its

upper and lower sides, the blank material 40 adjacent said sloping surfaces strengthening the projection against deleterious distortion during assembly of the cell case.

3. A blank for a cell case providing a slot having two interruptions therein, one extending partially across the slot and the other extending completely across the slot, the interruption which extends partially across the slot being formed by a projection having sloping surfaces at both its upper 50 and lower sides, said interruption which extends completely across the slot being relatively short, thereby to minimize the distance through which a similar intersecting blank must be moved with the blanks under substantial distortional strain during assembly 55 of the cell case.

4. A cell case comprising intersecting slotted blanks, at least one of said blanks having a depending portion adapted to be 60 folded laterally and extend beneath the contents of at least one of the cells provided by said cell case.

5. A blank for a cell case having a main body portion having transverse slots extending partially thereacross and at one side thereof and adapted to serve as a partition and a supplemental part opposite the slotted part of the blank adapted to be folded on a line extending longitudinally of the blank 70 and, when folded approximately 90°, to provide a lip extending beneath the contents of a row of cells adjacent the blank when assembled with other slotted blanks to provide a cell case.

In testimony whereof, I have signed my name to this specification.

ARTHUR H. SHOWALTER.
